UNITED STATES PATENT OFFICE.

DANIEL P. MULLINS, OF CHICAGO, ILLINOIS, ASSIGNOR OF ONE-HALF TO
DOUGLAS H. BERGH, OF SAME PLACE.

GARMENT-STRETCHER.

SPECIFICATION forming part of Letters Patent No. 373,027, dated November 8, 1887.

Application filed April 28, 1887. Serial No. 236,447. (No model.)

To all whom it may concern:

Be it known that I, DANIEL P. MULLINS, of Chicago, county of Cook, and State of Illinois, have invented certain new and useful Improvements in Garment-Stretchers, of which the following is a full, clear, and exact description, that will enable others to make and use the same, reference being had to the accompanying drawings, forming a part of this specification.

The object of this invention is to provide a device that is more especially intended for stretching and restoring pantaloons to their original shape; and the same consists of certain novel features in the construction, combination, and operation of the several parts, as will be hereinafter set forth in detail, and pointed out in the claim.

Figure 1 is a side elevation of a device embodying my improved features; Fig. 2, a transverse section in the plane 2, Fig. 1.

The upper end consists of duplicate transverse bars A A, and the lower end of the companion bars B B. The upper bars are adjustably secured in relation to each other by means of the thumb-screws a a' , the bars forming the lower end being secured in a similar manner by the thumb-screws a^2 a^3 . The waist and legs of the pantaloons are clamped between these bars, as indicated by dotted lines in Fig. 1, and shown in Fig. 2.

The outer ends of the system of toggle-levers D D' D² D³ are mounted on the thumb-screws placed at the four corners of the device, which form a pivotal bearing for the same. Normally these toggle-levers occupy a diagonal position relative to the end bars and run inwardly in the direction of each other, as shown in Fig. 1. The inner or joining ends of the levers D D' overlap and are secured to-

gether by means of the thumb-screw b, while the joining ends of the companion levers D² D³ are secured by the thumb-screw b'. The thumb-screws b b' form pivotal bearings for the joining ends of the toggle-levers, which, as they are moved outwardly from each other, grow longer and strain or stretch the article clamped in the end bars.

The locking-brace E is arranged parallel to the plane of the clamping-bars A A and B B, one end of said brace being pivoted to the toggle-levers D D' at their joint, and the other end provided with the slot d and having a longitudinal movement on the clamping-screw b', which secures the brace in proper position at right angles to the toggle-levers, and provides means for holding the latter at any point to which they may be adjusted. This arrangement provides a very efficient, inexpensive, and simple device for the purpose set forth.

Having thus described my invention, what I claim as new, and desire to secure by Letters Patent, is—

In a garment-stretcher, the combination, with the clamping-bars A A and B B, of the toggle-levers D D' and D² D³, interposed between and secured to the respective ends of said clamps, the locking-brace E, arranged parallel to the plane of the clamp, and pivoted to one part of the toggle-levers at their joint, and provided with the elongated slot d, and the means described for adjustably securing said brace to the other pair of toggle-levers at their joint, substantially as and for the purpose set forth.

DANIEL P. MULLINS.
